UNITED STATES PATENT OFFICE.

JOHN REMONTE, OF RANGER, TEXAS.

REFRIGERANT CONTAINER FOR COOLING APPARATUS.

Application filed January 21, 1926. Serial No. 82,703.

This invention relates to new and useful improvements in refrigerant containers for cooling apparatus.

The object of the invention is to provide a container for the brine or other heat absorbing fluid, whereby a maximum cooling area may be exposed in a minimum space.

A particular object of the invention is to provide a container arranged to expose an amplified cooling surface area to the air circulating in the refrigerating chamber, whereby the container may be placed in different positions, according to dimensions and shape of the chamber with equally good results and whereby relatively high temperatures at the top of the chamber will be reduced and temperatures approximating the melting point of ice will be maintained throughout the chamber.

20 An important feature is the provision of hollow wall flues for the circulation of the heat absorbing fluid therethrough, whereby the inner and outer surfaces of the flues are exposed for cooling the air circulating through and around said flues.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a front elevation of a container constructed in accordance with my invention,

Fig. 2 is a vertical sectional view taken on the line 2—2 of Fig. 1,

Fig. 3 is a side elevation,

Fig. 4 is a plan view and

Fig. 5 is a transverse sectional view taken on the line 5—5 of Fig. 3.

In the drawings the numeral 10 designates an upper horizontal head or manifold and 11 a lower horizontal head or manifold. The head 10 comprises top and bottom plates 12 and 13 respectively, extending substantially parallel and connected by short upright side walls 14. These parts are substantially duplicated at 12', 13' and 14' in the lower head 11. The plates of each head are spaced in close relation so as to provide a comparatively shallow flat circulating interior.

A coil compartment 15 extends centrally from the front of the container and has a front wall 16 continuous with the side wall

14' of the lower head. The rear wall 17 and the side walls 18 of the compartment extend from the top plate 12' of the lower head to the bottom 13 of the upper head. 60 From this it will be seen that a brine or other heat exchanging solution placed in the compartment will flow laterally into the heads over and under the walls 13 and 12'. The upper end of the compartment is open 65 at the top plate 12 and is surrounded by an upright flange 19 extending above the top plate and receiving a lid 20.

The front wall 16 has a circular or other opening 21 through which connection is 70 made with a cooling or refrigerating coil (not shown) which is located in the compartment 15. The opening 21 is suitably sealed so that the solution cannot leak out therethrough. However it is to be understood 75 that the solution in the compartment may be cooled in any suitable manner and its particular size and shape may be altered to suit conditions.

The heads of course extend laterally on 80 three sides of the compartment and a very important feature of the invention resides in hollow-wall flues each composed of an inner cylindrical tube 22 and an outer cylindrical sleeve 23 concentrically surrounding the tube. Each tube is open at its ends 85 and is secured in openings in the bottom plate 13' and top plate 12; while each sleeve 23 has its lower end fastening in an opening in the top plate 12' and its upper end fastened in an opening in the bottom plate 13.

This arrangement provides a vertical circular space or column between each tube and its sleeve connecting the upper and lower heads. Such a structure exposes the inner 95 surface of the tube to the air passing through the flue; while the outer surface of the sleeve is exposed to the air passing through and along the same. I have two of such flues on each side of the compartment 15 and three flues across the back of the container in rear of said compartment. However it is to be understood that any number of flues of any suitable shape may be employed.

100 The heat exchanging fluid, due to changes in temperature at different elevations will circulate through the heads 10 and 11 and through the walls of the flues. These flues are spaced from the walls 17 and 18 and thus 105 said walls, the top, bottom and sides of the heads and the inner and outer surfaces of

the flues are exposed to the air circulating in the refrigerating chamber in which the container is placed. These amplified cooling or heat absorbing surfaces are so 5 extensive as to greatly increase the cooling efficiency and also to cause the maintenance of a more even temperature in the chamber.

While the container is usually installed in the refrigerating chamber with its flues upright it is also designed to be installed with 10 the flues horizontally, in such later cases the lid 20 being sealed against leakage or its location changed. One of the important 15 advantages resulting from the use of this container and due to the maintenance of a low temperature, is the reduction of the refrigerating capacity which results in a saving in power and operating expense. Experiments have demonstrated that by installing this container a much smaller and 20 less expensive refrigerating unit may be used.

Various changes in the size and shape of the different parts, as well as modifications 25 and alterations may be made within the scope of the appended claims.

What I claim, is:

1. A closed container for heat exchanging liquid comprising opposite heads each 30 having an inner and outer wall, a refrigerat-

ing compartment for a body of said liquid communicating with said heads, and spaced flues connecting the heads with an inner wall attached to the outer walls of each head and an outer wall attached to the inner walls of the heads, said flues having their inner and outer walls exposed to atmosphere and communicating with the heads at the ends of the outer flue walls to effect a circulation of the liquid from the compartment and intermediate the flue walls by heat exchange therefrom. 35

2. A refrigerant container comprising upper and lower heads each having inner and outer plates, a refrigerating compartment extending from the inner plate of the lower head to the inner plate of the upper head, a front wall enclosing the compartment, and a plurality of spaced flues connecting the heads outside of the compartment, 40 each flue comprising an inner tube connecting the outer plates of the heads and a surrounding sleeve connecting the inner plates of the heads, whereby the space between the flue walls and heads is in communication 45 with the refrigerating compartment for the thermo-circulation of a cooling fluid. 50

In testimony whereof I affix my signature.

JOHN REMONTE.
